UNITED STATES PATENT OFFICE

2,625,942

ILLUMINATED VANITY CASE

Henry Charles Weiss, Jr., Sturtevant, Wis.

Application February 21, 1949, Serial No. 77,471

1 Claim. (Cl. 132—83)

1

This invention relates to improvements in vanity cases and more particularly to a novel illuminated vanity case.

An object of the invention is to provide a device of the type having means for throwing light upwardly through an aperture properly formed therein whereby the case may be held substantially level with the illumination properly cast on the features of the user.

Another object of the invention is to so position the mirror in the vanity case cover that it will more efficiently reflect the light cast by the illuminating means.

Other and further objects of the invention will appear as the description proceeds, reference being had to the accompanying drawing, in which:

Fig. 1 is a view in perspective of a vanity case embodying the invention.

Fig. 2 is a view of the light operating plunger and retaining plug for the same.

Fig. 3 is an exploded view of the vanity case and light mechanism.

Fig. 4 is a view on line 4—4 of Fig. 3.

Fig. 5 is a fragmentary view of a corner of the case.

Referring more particularly to the drawing, the numeral 10 refers to the vanity case generally, having a powder receptacle portion 11, with a cover 12 hinged at 13 and provided with a mirror 14 disposed on a lateral angle within said cover 12. The case 10 has a battery compartment at 15 thereof disposed longitudinally of the case 10 and having an upwardly inclined aperture at 16 adapted to emit light rays from the bulb 17 when the latter is energized by the battery 18. One end of the battery compartment 15 is threaded at 19 to receive the threaded plug 20 which is centrally apertured to accommodate the push button 21 which latter has a shoulder at 22. A coil spring member 23 threadedly receives the threaded bulb 17 and has a projection 24 which forms a contact with the side wall of the dry cell 18. The case 10 has the conventional closure latch 25.

In use, the cover 12 may be opened by releasing the latch 25 so that the mirror 14 may be tipped

2

back in a convenient position for use while the case 10 is held on a level plane. The button 21 may then be pushed inwardly and tilted slightly to one side so as to engage the shoulder 22 which will serve to maintain a closed circuit as long as desired. When the button 21 has been pushed inwardly, the contact terminal 26 of battery 18 will bear against the contact terminal 27 centrally of the bulb 17, thus completing the circuit to energize the bulb. The aperture at 16 being slightly upturned will throw the light on the user's face, even though the compact or vanity case is held on a level plane, thus insuring against spillage of the contents of the case 10.

10 15 The push button may be operated either with or without utilizing the shoulder 22, and if said shoulder is not engaged within the plug 20, release of the button will allow the spring member 23 to separate the contact terminals 26 and 27 and so break the circuit to turn off the light.

Having thus described the invention, it will be seen that various modifications in structure and design may be employed without departing from the spirit of the appended claim.

20 25 What is claimed and desired to be secured by Letters Patent of the United States, is:

In a vanity case having a powder compartment to one side of the center thereof, a cover positioned off-center over said compartment hinged to open away from the user, and a mirror inside of said cover laterally inclined with respect thereto to compensate for the off-center position of said cover.

HENRY CHARLES WEISS, JR.
